UNITED STATES PATENT OFFICE.

HARRY M. DALTON AND CHARLES M. CONKLIN, OF CINCINNATI, OHIO.

CARBURETER.

1,087,218.

Specification of Letters Patent.

Patented Feb. 17, 1914.

Application filed August 9, 1912. Serial No. 714,296.

To all whom it may concern:

Be it known that we, HARRY M. DALTON and CHARLES M. CONKLIN, citizens of the United States, residing at Cincinnati, in the county of Hamilton and State of Ohio, have invented certain new and useful Improvements in Carbureters; and we do hereby declare the following to be a full, clear, and exact description of the invention, such as

10 will enable others skilled in the art to which it appertains to make and use the same.

Our invention relates to carbureters, such as are in use in connection with internal combustion engines, and the object of the invention is to provide a carbureter of this type, capable of adjustment to normal conditions of operation and being provided with means whereby under varying conditions the required volume of fuel may be 20 supplied and the required volume of air automatically added thereto, to effect the proper working of the engine, and it will be noted that by our improvement, the necessity of a float valve is obviated.

25 The invention is clearly illustrated in the accompanying drawings, in which;

Figure 1 is a vertical sectional view of our improved carbureter, through the outlet to the engine. Fig. 2 is a vertical sectional view transverse to that shown in Fig. 1. Fig. 3 is a plan view of the base of the carbureter. Fig. 4 is a bottom plan view of the main body of the carbureter. Fig. 5 is a sectional view of a securing collar for 35 the torsion wire. Fig. 6 is a top view of the same. Fig. 7 is a plan view of collar and handle for controlling the torsion wire.

1 represents the main body of the carbureter provided with the extension 2 in which 40 is placed a suitable throttle for the engine. The main body 1 is mounted upon a base 3, in which it is secured by screws 4 or other suitable means. The base 3 is open and is provided with a bridge 5, hollow for a portion 45 of its length to admit a supply of fluid fuel, to the vertical tubular part 6 which is preferably integral with the bridge 5 and is provided with vertical slots 7. The upper end of the tubular part 6 is screw 50 threaded and engages the internally screw threaded part 8, the upper portion of which is of a substantially inverted cone shape with a laterally extending flange 10 and is provided with apertures 11.

55 12 is what may be termed a primary needle valve, engaging a seat in the lower end

of the tubular part 6 and is provided with a hollow stem 13, the upper end of which is adapted to seat itself in the secondary valve seat 14 formed in the hollow plug 15 secured in said tubular part 6 and provided at its upper end with a seat for the secondary needle valve 28. The lower end of the hollow valve stem is reduced and the reduced portion is provided with apertures 65 opening into the interior of the stem.

16 is a flanged valve sleeve mounted on the tubular part 6, the flanged portion normally supporting the primary air valve 17 provided with apertures 18. Mounted upon 70 the sleeve 16 is a flange washer 19. A pin 20 passes through the sleeve and slots in the tubular part 6 and the stem of the primary needle valve, and is adapted to lie within the upturned flange of the washer. Between the valve 17 and the flanged washer, there is disposed the coiled spring 75 21 which, however, normally exerts no pressure on the primary needle valve, but is held under normal compression between the primary air valve 17 and the washer 19 by the flange on the sleeve 16 and the pin 20, passing through the upper end of said sleeve. The combined parts, to wit, the primary air valve, the sleeve 16, washer 19 and spring, 80 form a weight which tends to hold the primary needle valve upon its lower seat. When, however, suction is created, these connected parts move bodily upward, carrying the primary needle valve with them, 85 until said valve engages its upper or secondary seat, after which any further upward movement of the primary air valve will further compress the spring 21.

22 is an annular shell of substantially the 90 form of the frustum of a cone, shown in the drawing, and is provided with outwardly extending flanges adapted to slidably engage the sides of the main body 1, and an inwardly extending flange adapted to rest normally on the outwardly extending flange 10 100 of the part 8. Extending over the shell 22, is a bridge wire 23 which engages notches in the outwardly extending flange 24 of the shell 22.

105 25 is a valve stem, screw threaded at its upper extremity to engage an internally screw threaded support 26, which is also provided with exterior screw threads to engage a similarly screw threaded vertical 110 flange 27, provided in the top of the main body. The threads of the stem 25 and those

2
of the part 26 are of different pitch, securing a differential action, and the operator is enabled to effect the proper adjustment with the greatest accuracy. The lower end of the 5 valve stem 25 is provided with a secondary needle valve 28, mounted in a socket in said stem adapted to engage a valve seat in the upper end of the plug 15 as shown. The valve stem 25 is flattened or squared at a 10 portion of its length and said portion is provided with a vertical slot 29. Upon the flattened or square portion there is movably mounted a slide 30, the lower portion of which is provided with a slot 31 registering 15 with the slot in the valve stem and having an outwardly extending flange 32.

The top 33 of the main body 1, is provided with a curved slot 34 and a collar 35 is loosely mounted upon the lower portion of 20 the vertical flange 27, the said collar having a screw threaded opening to be engaged by a screw 38, which passes through a collar 39 having an arm or projection 40 loosely mounted on the upper portion of the flange 25 27, said screw passes through the slot 34 in the top of the main body and is adapted to engage a screw threaded opening in the collar 35. Between the collar 35 and the slide 30 of the valve stem 25, there is interposed 30 a tension spring 42 and the bridge wire 23 passes through the slots in the slide and valve stem.

43 is a torsion wire, one end of which is secured in the collar 35; the other end of 35 said torsion wire passes loosely through an opening in the flange 10 of the inverted cone shaped part 8, said torsion wire engaging the bridge wire preferably by means of a sliding yoke 44.

40 45 is a hand wheel keyed to the part 26.

The operation of the device is as follows: The fuel enters the carburetor through the bore in the base and is controlled by the primary needle valve 12, which operates 45 the tubular part 6, permanently attached to the bridge 5, in the base of the carburetor. When suction is created by cranking the engine, the primary air valve 17 is raised admitting air into the body of the carburetor 50 through the openings 18 and at the same time raising the valve sleeve 13, the flange 19 and pin 20 which passes through the stem of the primary needle valve, thus raising said valve and admitting fuel which passes 55 through the hollow stem 13 of the primary needle valve, escapes through slots in the valve stem and mixes with the inflowing air within the shell 22, the mixture passing out through apertures 11 above the secondary 60 valve seat. This forms the priming or initial charge for the engine, but as the engine continues to move, greater suction is created and the primary needle valve is carried up until it seats itself at 14, thus closing the 65 slots 7, after which no fuel can escape into

the body of the carburetor except that which passes the secondary valve 28. Should additional upward pressure be exerted on the primary air valve by increased suction, the spring 21 will be compressed, permitting 70 said valve to yield upwardly while still holding the upper end of the primary needle valve in engagement with its upper seat 14. The secondary valve 28 is mounted in a socket in the lower end of the valve stem 25. In the meanwhile a proper amount of twist 75 has been given the torsion wire 43, by turning the handle 40 of the collar 39, said twist being maintained by the screw 38. As still greater suction is created, the shell 22 is raised and is turned by the torsion wire. The bridge moving with it, turns the valve stem and the threaded portion of the same raises the valve an additional amount depending upon the force of the suction and the amount of curvature given to the torsion wire, by the movement of the collars 35 and 39, thereby permitting any desired amount of fuel to be automatically supplied according to the speed of the engine. 80

It will be noted that under a light draft or suction through the throttle, the shell 22 forms the mixing chamber and under increased draft or suction, the space within the main body above the shell, becomes the 85 mixing chamber. 90

What we claim and desire to secure by Letters Patent is:

1. In a carburetor, provided with air inlet and mixture outlet, and fuel inlet adjacent to the air inlet, a primary air valve for said air inlet, a primary fuel valve for said fuel inlet, a secondary air valve within the carburetor forming a preliminary mixing chamber adjacent to the primary inlet valve, the carburetor being provided with a passage 100 for the mixture from said mixing chamber to the outlet, independent of said secondary air valve, a secondary fuel valve, between said secondary air valve and the mixture outlet, means connected with the primary air inlet valve for preventing the admission of fuel by the primary fuel inlet valve during heavy suction, and means actuated by the secondary air valve for opening the 105 secondary fuel inlet valve. 110

2. In a carburetor provided with an air inlet and a mixture outlet, of an air inlet valve, a fuel inlet adjacent to the air inlet and a fuel inlet valve therefor, a secondary air valve interposed between the air inlet and mixture outlet, and forming a preliminary mixing chamber, said carburetor being provided with a passage independent of the secondary air valve from said preliminary 120 mixing chamber to the mixture outlet, a primary inlet valve controlling the supply of fuel to the preliminary mixing chamber, said carburetor having a passage from the primary fuel inlet valve to the preliminary 125 130

- mixing chamber a part connected with the primary fuel valve for closing said passage, connections between the air inlet valve and the primary fuel valve for operating the latter, a secondary fuel inlet between the secondary air valve and the mixture outlet, and operative connections between the said secondary air valve and the secondary fuel valve.
- 10 3. In a carbureter provided with an air inlet, and mixture outlet, and a fuel inlet adjacent to the air inlet, a secondary air valve providing a preliminary mixing chamber between it and the air inlet, said carbureter having a passage connecting said preliminary mixing chamber with the outlet, independently of said secondary air valve, a primary air valve for the air inlet, a primary fuel valve, a yielding connection between the air inlet valve and the primary fuel valve, means for arresting the primary fuel valve, when moved by the primary air valve, whereby the primary air valve may be moved by increased suction with respect to the primary air valve, a secondary fuel inlet between the secondary air valve and the mixture outlet, a secondary fuel valve controlling the same and connections between the secondary air valve and the secondary fuel valve.
- 15 4. In a carbureter the combination with a casing having an air inlet aperture adjacent to one end and a mixture outlet adjacent to the other end, a liquid fuel inlet adjacent to the air inlet, and located centrally thereof, a primary needle valve normally closing said fuel inlet, and provided with a longitudinal fuel passage, a primary air valve for the air inlet connected with said fuel valve and holding the latter normally in closed position, a stationary part located above the needle valve, separated therefrom when the valve is in normal position, said part having a longitudinal passage to register with that in the said valve, a secondary air valve forming a preliminary mixing chamber adjacent to the primary air and fuel valves, said carbureter having a passage from the preliminary mixing chamber to the outlet independent of the secondary air valve, a secondary fuel valve normally closing the longitudinal fuel passage in said stationary part, and operative connections between said secondary air valve and said secondary fuel valve.
- 20 5. In a carbureter, the combination with air and fuel inlets, of valves for normally closing the same, a passage through said fuel inlet valve, an additional fuel passage at one end of said fuel inlet valve in line with the passage in said valve, but separated therefrom, a supplemental fuel valve for said additional passage, and means whereby a heavy draft or suction will bring the inlet valve in connection with the said additional fuel passage and actuate the supplemental fuel valve to increase the fuel supply.
- 25 6. In a carbureter, the combination with air and fuel inlets, of valves normally closing the same, the said fuel inlet valve having a passage therethrough, an additional air valve of the form of a frustum of a cone, means for moving said fuel inlet valve to discharge within the said additional air valve under light draft, and means for causing said fuel inlet valve to discharge in the body of the carbureter above the said additional air valve under heavy draft or suction.
- 30 7. In a carbureter, the combination with air and fuel inlets, of valves normally closing the same, but adapted to be opened by light draft or suction, of a supplemental fuel valve, an additional air valve operable by a heavy draft or suction to admit a greater amount of air, and means connecting said supplemental and additional valves whereby a movement of said additional air valves will move the supplemental fuel valve to admit a greater amount of fuel.
- 35 8. In a carbureter, the combination with an additional air valve to admit a greater flow of air under a heavy draft or suction, of a supplemental fuel valve having a slotted valve stem, said additional air valve being provided with a yoke passing through said slot of the said valve stem, and a means for turning said additional air valve and yoke to turn said valve stem to increase the amount of fuel when said additional air valve is moved.
- 40 9. In a carbureter, the combination with the additional air valve to admit a greater flow of air under heavy draft or suction, of a supplemental fuel valve having a slotted stem, supported by a threaded connection with the main body of the carbureter, said additional air valve being provided with a yoke passing through the slot of the supplemental valve stem and means to turn the additional air valve and its yoke when said valve is moved, to cause the threaded connection of the said valve stem to raise said stem and valve.
- 45 10. In a carbureter, the combination with primary air and fuel inlet valves adapted to be operated by light draft or suction, of an additional air valve to admit a greater flow of air under a heavy draft or suction, a supplemental fuel valve, supported by a threaded connection of its stem with the main body of the carbureter, said additional air valve being connected with the supplemental fuel valve by means whereby a movement of the additional air valve will turn the supplemental valve stem to cause its threaded connection to increase the supply of fuel, and means to vary the extent of the movement of the supplemental valve from like movements of the said additional air valve.

11. In a carbureter, the combination with primary air and fuel inlet valves to be operated under light draft or suction, of an additional air valve adapted to be operated 5 under heavy draft or suction, means whereby said additional air valve forms a chamber above the same, discharge passages for the primary air and fuel valves whereby the interior of the said additional air valve is 10 made the mixing chamber under a light draft or suction, and further discharging

means whereby the chamber above the said additional valve is made the mixing chamber under heavy pressure.

In testimony whereof we affix our signatures, in the presence of two witnesses.
